UNITED STATES PATENT OFFICE.

THOMAS SHIPLEY, OF YORK, PENNSYLVANIA.

APPARATUS FOR THE MANUFACTURE OF ICE.

1,356,317.

Specification of Letters Patent.

Patented Oct. 19, 1920.

Application filed January 12, 1920. Serial No. 350,728.

To all whom it may concern:

Be it known that I, THOMAS SHIPLEY, a citizen of the United States, and a resident of the city of York, in the county of York and State of Pennsylvania, have invented 5 a new and useful Improvement in Apparatus for the Manufacture of Ice, of which the following is a specification.

My invention has to do with ice-freezing cans for use in the can system of making ice wherein air under pressure is injected into the body of water in the can to prevent impurities in the water from being incorporated in the ice during the freezing operation—the air for this purpose being led through a tube to a point at or near the bottom of the can, where it is discharged into the water in the can. It is the preferred practice to lead the air tube, or blowing tube, as it is termed, upon the exterior of one of the sides of the can down from the top to the point at or near the bottom thereof where it discharges into the can, and in order to protect the exposed portion of the blowing tube from injury due to careless handling, and for other reasons, there has been formed in the side of the can an external groove in which the exposed length of the blowing tube is received and, as it were, housed, so as not to protrude laterally beyond the outer face of the body of the can as shown in my U. S. Patent No. 1,158,320 of October 26, 1915. The blowing tube at its ends is held securely in place 30 in the groove—at its lower end by its fluid tight attachment to the body of the can at the point where it enters the same, and at its upper end by the usual wrought iron band which encircles the top of the can, extending crosswise over the groove in which the blowing tube is seated and serving as a strap or plate to confine the tube therein. Owing, however, to the considerable length 40 of the exposed portion of the tube between its two ends—between $3\frac{1}{2}$ and $4\frac{1}{2}$ feet, roughly speaking, according to the size of the can—it has been found necessary, or desirable, to provide some means for holding it in place at one or more intermediate 45 points between its ends, depending upon the length of the tube. To solder the tube to the can at these intermediate points is objectionable for various reasons, and, from causes not necessary here to specify, not infrequently results in the ripping or bursting of the tube. On the other hand, straps,

serving the same purpose as the top band so far as holding the tube in place in the groove is concerned, form objectionable projections upon the exterior of the can. It is 60 my object to provide an efficient device for this purpose which shall not be open to any of these objections. To which end my invention consists of the means which I shall proceed first to describe in connection with 65 the accompanying drawings forming part of the specification, and then to point out more particularly in the claims;

In the drawings:

Figure 1 is a view of an ice-freezing can 70 embodying my improvement, broken off at the top.

Fig. 2 is an enlarged vertical section through the air tube side of the can on line 2—2, Fig. 1.

Fig. 3 is a cross section on line 3—3, Fig. 2.

Figs. 4 and 5 are cross sections on lines 4—4 and 5—5, respectively, Fig. 2.

Figs. 3, 4, 5 are on larger scale than Fig. 80 2 in order to show more clearly the construction.

The can shown in the drawing in connection with my improvement, is the form of can illustrated in my Letters Patent No. 85 1,158,320 hereinbefore mentioned. It will, however, be understood that my improvement is equally applicable to any other form of freezing can provided with a blowing tube contained in an external groove on one 90 of the sides of the can.

A is the sheet metal can of any preferred construction and of rectangular cross section in the present instance. B is the wrought iron reinforcing band at the top 95 of the can. C is the vertical external blowing tube-receiving groove of approximately U or V-cross section formed in one of the sides of the can, and extending from the top to a point near the bottom of the can. D is the blowing tube, preferably of semi-hard brass, inserted in the groove C from the top of the can, between the band B and the grooved side of the can and extending down in the groove and through an opening 100 in the lower end of the latter into the inside of the can, with its beveled lower end near enough to the bottom of the can to insure proper circulation of the air discharged from it. At the point where the tube passes 110 through the wall at the lower end of the groove from the outside to the inside of the

can, the tube and can are soldered together to make a fluid tight joint. The portion of the air tube which lies under the band B is cylindrical, and in practice is reamed out 5 on a taper to receive the usual air supply elbow nozzle indicated in dotted lines in Fig. 2. Below this point the tube preferably is of such cross-sectional dimensions relatively to the depth of the groove that 10 it is wholly contained within the groove, and is preferably flattened on its exposed side as shown.

As thus far described there is nothing new in the can over and above what is to be 15 found in my Patent No. 1,158,320, hereinbefore mentioned. I come now to the features which characterize my present improvement.

In order to secure the blowing tube from 20 lateral displacement, I provide at one or more points in its length, between its top where it is confined in place in the groove by the band B, and its lower end where it is soldered to the can at the point of its 25 passage through the end of the groove into the inside of the can, a retaining sleeve E preferably of soft brass, which, as shown in Figs. 2 and 3, is of a cross-section similar to the blowing tube but of sufficiently greater 30 internal dimensions to receive and fit around the latter without unduly binding it. The sleeve, seated in the groove in the can at the proper point, is there secured in place, 35 preferably by soldering to the body of the can along the outer edges of the groove and the tapered side of the sleeve, as indicated at f. The sleeve preferably is of such dimensions relatively to the depth of the groove in which it is held that its exposed 40 side will not project laterally beyond the groove, thus shielding and protecting it from accidental injury in handling the can. The blowing tube being of less dimensions than the sleeve through which it passes, 45 will be thus safely held against lateral displacement and retained within the compass of the groove. At the same time the fit between the tube and its encompassing sleeve is sufficiently loose to permit perfect freedom of movement to the tube, and to compensate and allow for variations in the expansion and contraction between the can and the tube, due to the difference in the 50 metal of which they are made.

55 The upper end of the blowing tube into which the air blowing elbow nozzle is inserted is liable to be swaged out of shape by rough handling of the nozzle in removing it from the tube or by the bobbing up

of the can due to the buoyant effect of the 60 brine in which it is immersed, resulting in sharp contact of the elbow nozzle with the tank cover. To remedy this trouble I provide the upper cylindrical portion of the blowing tube with a reinforcing ferrule G 65 which closely surrounds and is sweated or otherwise tightly secured upon the tube. The increase in the depth of the tube receiving groove due to the employment of the sleeve is sufficient to accommodate the 70 ferrule B also without protruding laterally from the groove so as to bind against the band B which covers it. The ferrule G thus serves not only to reinforce the upper end of the blowing tube, but also to steady 75 it and prevent it from rattling or shaking in the groove. The blowing tube, indeed, is held fast only at its lower end where it is soldered to the can, and above that point throughout its length it is free to move in 80 the groove independently of the can, and the devices which retain it in the groove, to compensate for difference in contraction and expansion due to the difference in the metals 85 of which they are composed.

I have shown but one retaining sleeve E in the drawing, but of course there may be as many as desired, placed at intervals apart on the blowing tube as the length of the blowing tube and other considerations may 90 demand.

Having described my improvement and the best way known to me of carrying the same into practical effect, what I claim herein as new and of my own invention and desire to secure by Letters Patent is as follows:—

1. A freezing can having in one of its sides an external vertical groove, a retaining sleeve contained within the compass of, 100 and secured in, said groove at a point intermediate the ends of the latter, and a blowing tube contained in said groove and extending through and loosely fitting within said sleeve, substantially as and for the purposes hereinbefore set forth.

2. In combination with the elements specified in claim 1, a band at the top of the can extending crosswise over the groove and covering the upper portion of the blowing tube 110 contained therein, and a reinforcing ferrule interposed between the said band and blowing tube and encircling and tightly secured to the latter under the arrangement and for the purposes hereinbefore set forth. 115

In testimony whereof I affix my signature.

THOMAS SHIPLEY.
